UNITED STATES PATENT OFFICE.

JACQUES BUSTANOBY, OF NEW YORK, N. Y.

HAND-MIRROR.

1,065,110.

Specification of Letters Patent. Patented June 17, 1913.

Application filed August 17, 1910. Serial No. 577,552.

To all whom it may concern:

Be it known that I, JACQUES BUSTANOBY, a citizen of the United States, and resident of the borough of Manhattan, city, county, and State of New York, have invented certain new and useful Improvements in Hand-Mirrors, of which the following is a specification.

My invention relates to hand mirrors, and 10 has for its object to so construct such a mirror that, without increasing its bulk or giving it an unsightly appearance, it may become adapted to carry cosmetic powder and a puff, also, in the preferred form of my 15 invention, a stick of rouge, these accessory toilet articles being so arranged that they will at no time interfere with the use of the mirror as such.

To carry out the purposes of my invention, I form the back of the mirror with a 20 chamber adapted to contain the powder and the puff, and my invention further consists in certain features and combinations that will be fully described hereinafter and particularly pointed out in the appended 25 claims.

Reference is to be had to the accompanying drawings, in which—

Figure 1 is a central vertical section 30 through one form of my improved mirror taken on line 1—1 of Fig. 2; Fig. 2 is a rear view thereof; Fig. 3 is a rear view of another form of my invention with parts in section, and Fig. 4 is a section taken on line 4—4 of Fig. 3.

As illustrated in Figs. 1 and 2 the mirror proper A has a curved back in which a central chamber A¹ is formed the walls A² of said chamber flaring forwardly, so 40 that with the mirror held upright, the bottom wall of the chamber is inclined downward from the opening at the rear end of the chamber toward the closed end of the chamber, adjacent to the mirror. Thus the 45 cosmetic powder B contained in the chamber A¹ will tend to slide away from the opening and will not be so liable to drop out when the chamber is open at the rear. A convenient way of constructing the back 50 is to make it of a plate A³ adjacent to the mirror proper, a conical wall A² to form the central chamber A¹, a bottom wall A⁶ for said chamber, and an ornamental shell A⁴. The parts A², A³, A⁴, A⁶ may be soldered

together or otherwise connected. At the 55 opening of the chamber A¹, a cylindrical portion A⁵ is formed, or this portion might flare slightly rearward, being adapted for tight frictional engagement with an annular portion H¹ on the puff H which in its main 60 features may be of ordinary construction having a central handle H² which projects rearwardly when the parts are put together as in Fig. 1.

The mirror is provided with a handle C 65 of appropriate shape. This handle may be recessed lengthwise as at C¹ to form a chamber for the reception of a stick of rouge D provided with a socket or holder D¹ made of sheet-metal or other suitable material, which 70 holder is fitted tightly against the walls of the chamber C¹ so that the stick itself will be held clear of engagement with said walls. The handle D² of the holder projects outwardly and downwardly from the handle C 75 of the mirror.

In the construction illustrated by Figs. 3 and 4, the puff H is not utilized as a cover for the powder chamber A¹, but a separate cover E is provided preferably hinged at 80 one side as at E¹ and combined with a spring F having a tendency either to close the cover E, or to open it, in which latter case a suitable catch G is supplied to hold the cover closed when desired. Upon pressing the 85 catch, the cover E will fly open, so that the puff H will be readily accessible.

It will be seen that a lady can hold the mirror (by the handle C) with the left hand and at the same time use the right hand to 90 manipulate the puff H to take powder from the chamber A¹ and apply it in the usual way; the mirror will remain undisturbed all this time. The same thing is true with respect to the stick of rouge D; this too, can 95 be handled while the mirror is held in its position of use. Fig. 3 shows the handle C provided with two chambers C² and C³ located side by side, one of them containing the stick of rouge D and the other a black 100 or colored pencil D³ having a holder D⁴ and handle D⁵ and serving to mark eyebrows, etc.

The improved mirror herein described combines two (three or four) articles in a convenient form, avoids the necessity of carrying these articles separately, and thus reduces their aggregate bulk, which is a great convenience particularly when traveling.

Each of the accessory articles, while practically concealed by the mirror when not used, is readily accessible for use, without at any time interfering with the employment of the 5 mirror as such.

Various modifications may be made without departing from the nature of my invention as defined in the appended claims.

I claim as my invention:

- 10 1. As a new article of manufacture, a frame having a back and a handle extending from said back at one side and substantially in the same plane with the back, the said back comprising a curved shell and a conical 15 wall connected with said shell, the axis of the cone being perpendicular to the plane of the back and the narrow open end of the cone being at the rear so as to form a rearwardly contracted receptacle open at the 20 rear, the back also comprising a wall which forms a bottom for said receptacle; and

means for closing the open end of said receptacle.

2. As a new article of manufacture, a frame having a back and a handle extending from said back at one side and substantially in the same plane with the back, the said back being provided with a rearwardly open receptacle, that wall of said receptacle which is nearest the handle, being inclined forwardly and toward the handle, so as to prevent the contents of said receptacle from dropping out when the frame is held upright, and means for closing the open rear end of said receptacle. 25 30 35

In testimony whereof, I have signed this specification in the presence of two subscribing witnesses.

JACQUES BUSTANOBY.
